UNITED STATES PATENT OFFICE.

JACOB R. FRY, OF NEW YORK, N. Y., ASSIGNOR TO WESTERN ELECTRIC COMPANY,
INCORPORATED, OF NEW YORK, N. Y., A CORPORATION OF NEW YORK.

ELECTROMAGNETIC DEVICE.

Application filed March 24, 1921. Serial No. 455,084.

To all whom it may concern:

Be it known that I, JACOB R. FRY, a citizen of the United States, residing at New York, in the county of Bronx, State of New York, have invented certain new and useful Improvements in Electromagnetic Devices, of which the following is a full, clear, concise, and exact description.

This invention relates to relays and particularly to relays of the electromagnetically polarized type.

The object of this invention is to provide a compact electromagnetic device having a plurality of windings with provision for connection of supply current at certain points to cause the device to function as a polarized relay responsive to direct current impulses of certain polarity or to alternating current energization, dependent on the nature of the current supply and method of its connection to the device.

A feature of this invention resides in an electromagnetic structure comprising a pair of E-shaped cores of magnetic material with a plurality of electrically continuous windings thereon and an armature member adapted to move in the space between said E-shaped cores to control circuit contact members associated therewith. The particular design of the yokes included in the magnetic structure employed in this invention makes the cores and armature associated therewith magnetically short, thereby greatly increasing the self-demagnetizing factor, that is, the ratio of the length of the magnetic path in iron to the cross section of the core.

This self-demagnetizing characteristic is very desirable in relays and particularly in relays used in telephone systems wherein the electromagnets are designed, in most cases, to operate on predetermined current values, so that any previous application of a magneto-motive force should, in no way, establish magnetic conditions in the relay, which would affect its operation upon a subsequent energization.

The device of this invention is particularly characterized by its combination of electric and magnetic circuits, wherein the electric circuits are such as to produce one magnetic flux in a circuit cutting through the armature at right angles thereto and a second magnetic flux in circuits including the armature as a path for this flux in opposing

directions in the adjacent parts of said armature. This device is also characterized by its efficient adaptation to use in a variety of circuits dependent on the nature of current supply and the method of connection of that supply to the energizing windings. For example, with a source of direct current properly connected to certain points in the windings, the device becomes a polarized relay and will respond to operating current impulses of certain polarity sent over a circuit connected at certain other points of the winding. In this case, the same windings are used for polarization and operation. If alternating current be applied at certain points in the winding and an auxiliary alternating current, in phase and of like frequency with the first mentioned alternating current, be applied at certain other points in the windings, the device operates in one direction during the period of application of the current. Direction of operation may be reversed by reversing the connection of the auxiliary alternating current.

A more complete understanding of these and other novel features may be had from the accompanying illustrative drawings and detailed description, in which Figure 1 discloses a perspective view of the device of this application with the energizing coils shown in section and the flux paths for contemplated circuits indicated on the two E-shaped magnetic cores.

Figure 2 discloses a circuit diagram of one embodiment of this invention, showing the relation of current flow to magnetic flux for operation of the armature, where the polarizing current and operating current are equal in amount.

Figure 3 is a modification of Figure 2 and diagrammatically illustrates the current relations in the windings of this relay when polarized with direct current operated by current pulses over a second circuit.

Figure 4 discloses a diagram of circuit relations for this relay for sustained operation when used in an alternating current circuit.

In detail there is disclosed in Figure 1, a pair of E-shaped magnetic cores 1 and 2 arranged with the end faces of similar members, end adjacent. On the central member of core 1 is a pair of energizing coils 3 and 4 and on the central member of core 2 is another pair of energizing coils 5 and 6. Though the coils are disclosed associated

with the central member of each core, it is obvious that they may be associated with other portions of the cores without alteration of the magnetic circuits. Located intermediate the adjacent end faces mentioned, is an armature 7 arranged to be mounted in trunnion bearings in the rear of the cores 1 and 2. This bearing is not disclosed in the drawing as its nature is well-known. The windings 3, 4, 5 and 6, when properly connected to each other and to a source of electrical energy set up magnetic flux in the paths shown in dash lines. It is to be noted, that this magnetic flux passes through the armature perpendicular to its length at three well defined locations on the armature, these locations being limited to the extent of the face of each magnetic core member. A spring 8 is disclosed as attached to the armature in such a position as to maintain the armature substantially mid-way between the magnetic cores 1 and 2 when the device is in its unoperated position. However it is to be understood that the spring may be attached at any appropriate point to create a retractile moment, or the armature may be of the reed type, in which case it is self retracting. Attached on one end of the armature is an insulating pin 9 cooperable with spring contact members 10, 11, 12 and 13, which members are electrically insulated from each other by insulating members 14 and are rigidly retained by a clamping means. It is to be noted that the magnetic cores 1 and 2 are disclosed as laminated in structure to prevent eddy current losses when the relay is used on alternating current circuits. Also it is to be expressly understood that spring 8 while disclosed as a spiral tension spring, may assume any form well-known and well adapted for the purpose intended and that insulating pin 9 and cooperable contact members 10, 11, 12 and 13 may be arranged in other positions cooperable with the armature to produce the same result as shown.

Referring to Figure 2 in detail, the apparatus of Figure 1 is shown in outline and the electric and magnetic circuits are shown for a condition of operation resulting from connection of a source of electrical energy 15 to two symmetrically opposite points in the closed coil circuit, and the connection of a second source of electrical energy associated with line wires 16 and 17 to the two remaining symmetrically opposite points in the coil circuit; this last mentioned source of electrical energy resulting in a flow of electric current being of the same amount as that sent out by source 15. Electrical source 15 for present discussion may be called the polarizing battery and the current flowing from this source, the polarizing current; the second source of electrical energy may be called the operating source of energy and its current

the operating current. Starting with the positive side of battery 15, current may be traced through windings 3 and 5 and return to the negative side of the battery. Also from the same positive terminal of battery 15, current may be traced through windings 6 and 4 and back to the negative terminal of the battery 15. The direction of this current flow is indicated in dash lines with arrow points properly placed. Current from the second electrical source which has been termed the operating current may be traced as coming in over line 16, through coils 3 and 6, and returning over line 17. Another and parallel path for this operating current may be traced from line 16 through coils 5 and 4 and returning over line 17. This operating current is indicated by solid lines with arrow points properly placed near the wires. Considering the polarizing and operating currents as indicated in the diagram, it will be seen that the conditions established in the above discussion will cause the two currents mentioned to nullify each other in coils 3 and 4 and to become additive in coils 5 and 6 with the result that no magnetic flux will be produced in any possible circuit in magnetic core 1, but that strong magnetic flux due to the combination of currents mentioned will be established in magnetic core 2, as disclosed in the diagram. It will be noted that the armature 7 is included as a portion of the return path for magnetic flux in the circuit just mentioned and that the flux is established in opposite directions in the two lengthwise halves of the armature. Reversal of the direction of operating current flow in wires 16 and 17 but keeping the operating and polarizing currents equal in amount, reverses the direction of operating current in the coils connected therewith. According to the usual laws of magnetic attraction the armature is drawn toward the strongest magnetic field. Thus selective operation in the relay is dependent only on the direction of flow of the operating current, assuming the polarizing current from source 15 to remain constant in direction. If the operating current be greater or less in amount than the polarizing current two complete sets of flux paths will be established but there will always be a preponderance of flux on one side or the other of the armature dependent on the relative directions of the polarizing and operating currents. Thus, the amount of current flow has no effect on the placement of the effective operating flux but only affects the amount of that flux. The placement of the effective operating flux is dependent entirely on the relative directions of polarizing and operating current flow. It is obvious from a study of the diagram in Figure 2 that the connections of polarizing and operating current may be interchanged without affecting the operation of the relay.

Figures 3 and 4 illustrate diagrammatically the electric circuits desirable for operation of the relay of this invention on direct current and on alternating current respectively, though it is apparent that the arrangement shown in Fig. 3 would operate on a combination of both direct and alternating currents, by the application of an alternating current source across the conductors 16 and 17. Referring particularly to Figure 4 there is disclosed a source of alternating current 18 connected to wires 16 and 17 and the said wires are connected to symmetrically opposite points in the closed coil circuit including coils 3, 5, 4 and 6. The primary winding 19 of a transformer is connected in series in line 17 and the secondary winding 20 of the said transformer has its terminals connected to the two remaining symmetrically opposite points in the relay coil circuit. With circuit connections as disclosed, the passage of alternating current over the wires 16 and 17 will induce a current in the secondary winding circuit 20 of the transformer substantially in time phase with the alternating current source. In the case of this circuit, it will be convenient to consider the current flowing over the line wires 16 and 17 and through the primary winding 19 of the transformer as the polarizing current and the current flowing in the secondary winding 20 of the transformer as the operating current. Since it is obvious that the currents in the polarizing and operating circuits reverse their direction of flow at the same time, a preponderance of magnetic flux can be established with connections as indicated on one side of the armature only, resulting in the attraction of the armature toward that side. Reversal of the terminal connections of the secondary winding 20 to the relay coil circuit results in a preponderance of magnetic flux being established on the opposite side of the armature from that just mentioned and an attraction of the armature in the opposite direction from the case just mentioned. Figure 2 may be taken as representing an instantaneous condition of current flow in the electrical circuit diagram of Figure 4, if the transformer connections associated with windings 19 and 20 be substituted for a source of direct current supply 15 shown in Figure 2.

What is claimed is:

1. In combination, a pair of E-shaped cores having corresponding members end adjacent, an armature cooperable with said magnetic cores in the space between said end adjacent members, windings for said magnetic cores, said windings so connected as to form a closed series circuit, a source of electrical energy connected to symmetrically opposite points in said series connected winding circuit, a second source of electrical

energy connected to other symmetrically opposite points in said series connected winding circuit in such manner as to nullify the magnetic flux produced by said first mentioned electrical source in the coils on one magnetic core and to amplify the magnetic flux produced by said first mentioned source in the coils on the other magnetic core. 70

2. In an electromagnetic structure, a pair of E-shaped magnetic cores with corresponding members end adjacent an armature cooperative therewith in the space between said cores, windings on said cores so connected to each other and to a source of electrical energy that magnetic flux is produced 80 in one direction throughout the adjacent middle members of said cores and in the opposite direction throughout the adjacent end members of said cores, cutting through the armature and at right angles thereto. 85

3. In an electromagnetic structure, a pair of E-shaped magnetic cores with corresponding members end adjacent, an armature cooperative therewith in the space between said cores, windings on said cores so 90 connected to each other and to two sources of electrical energy that magnetic flux is produced in one direction in the middle member of one core, in the opposite direction in the end members of the same core 95 and in opposing directions in the armature.

4. In an electromagnetic structure, a pair of E-shaped magnetic cores with corresponding members end adjacent, an armature cooperative therewith in the space between said cores, windings on said cores so connected to each other and to two sources of electrical energy that magnetic flux is produced in one direction throughout the adjacent middle members of said cores and 100 in the opposite direction throughout the adjacent end members of said cores cutting through the armature at right angles thereto and a second flux is produced including the members of one core only in the same direction as the first mentioned flux and the two halves of the armature in opposing directions as a portion of the return circuit. 110

5. A relay comprising two yokes having their poles facing each other, an armature positioned between said poles, windings for each of said yokes, a pair of terminals for the windings connected to a direct current source, and a second pair of terminals for said windings connected to an alternating current source, said windings being so related to said terminals that both direct and alternating current flow through both windings, said terminals connected to the direct current source being conjugate to the terminals connected to the alternating current source. 125

6. A relay comprising two yokes having their poles facing each other, an armature positioned between said poles, windings for 130

each of said yokes, a pair of terminals for the windings connected to a direct current source, a second pair of terminals for said windings connected to an alternating current source, said windings being so related to said terminals that both direct and alternating current flow through both windings, said terminals connected to the alternating current source being conjugate to the terminals connected to the direct current source.

7. A relay comprising two yokes having their poles facing each other, a winding for

each yoke connected in bridged relation to the opposite yoke, an armature positioned between said yokes and controlled by the electromagnetic condition thereof, a source of alternating current, a source of direct current and terminals for interchangeably connecting said windings with either of said sources of current whereby said armature is caused to assume a neutral position between the poles of said yoke.

In witness whereof I hereunto subscribe my name this 21 day of March, A. D., 1921.

JACOB R. FRY.
